UNITED STATES PATENT OFFICE.

GEORGE O. OLSEN, OF LOS ANGELES, CALIFORNIA.

SHIRT.

Application filed January 28, 1925. Serial No. 5,344.

My present invention has reference to an outer shirt for men.

An object is to produce a shirt which can be worn for at least twice the length of time in which a shirt of the ordinary construction is used.

A further object is to produce a reversible shirt, that is, a shirt in which either side thereof may be alternately used as the front 10 of the shirt, and in which the cuffs are foldable so that the outer portion or fold thereof may be arranged either upon the inner or outer faces of the sleeves, and further in which the respective faces of the shirt, including the sleeves may be differently colored so that the shirt will present different effects or designs when worn in reverse positions by the user.

With the above broadly stated objects in view and others which will appear as the nature of the invention is better understood, reference is to be had to the drawings which accompany and which form part of this application.

25 In the drawings:—

Figure 1 is a perspective view of a shirt in accordance with this invention.

Figure 2 is a top plan view thereof.

30 Figure 3 is an approximately central transverse sectional view through the body of the shirt.

Figure 4 is a perspective view of the sleeve showing the folds of the cuff in one position.

35 Figure 5 is a similar view showing the fold of the cuff in a reverse position to that disclosed in Figure 4.

While in the showing of the drawings I have disclosed a shirt whose front and rear are of different materials, it is to be understood that both the front and back may be of the same material and design. My shirt is constructed in view of economy and is primarily designed for the poorer class of men. It is well known that men's shirts are liable 40 to the most wear around the collar band. This is sometimes occasioned by the points of the collar contacting the shirt at this part, but primarily because of the different materials between the band and the body of the shirt so that the softer body, during the washing of the garment, becomes worn or torn. The body of the shirt is of soft material, and as both sides of the garment may be worn as the front, it may be found desirable 45 to construct the sides of material hav-

ing different designs. For distinction, I will indicate one side of the body by the numeral 1 and the opposite side by the numeral 2. These sides have their edges stitched together and are formed with the sleeves 3 in 60 the usual manner. The cuffs 4 of the sleeves are of the fold type and the outer or fold portion of the said cuffs, for distinction, are indicated in the drawings by the numeral 5. The bodies 1 and 2 are centrally opened, and 65 the over and underlying lapping portions thereof are connected together by the usual buttons 6 on the underlying portions of the garment that are received through button-holes in the overlying portions of the garment. The button holes and the heads of the buttons are concealed by flaps 7 that are stitched to the outer face of the body portions 1 and 2. The collar band 8 is also constructed of two sections stitched to the 70 neck portion of the sectional bodies 1 and 2 and provided with the usual lapping portions formed with the openings for the collar buttons.

75 From the foregoing it will be apparent 80 that either side of the shirt may be worn as the front thereof, and the folds of the cuffs may be arranged inwardly or outwardly, as disclosed in Figures 4 and 5 of the drawings to correspond with the material on the body 85 providing the front of the shirt.

Having described the invention, I claim:—

An outer garment comprising two similar sections adapted to be connected to each other to provide a shirt and including lapping edges at the opposite sides of the center of the shirt, covered interengaging means for said lapping edges, a collar band section for each similar section and being likewise lapping and formed with button openings 90 at the lapped edges thereof, said similar sections including cuffed sleeves and together with the sleeves being formed by and equally divided into material of different design, the cuffs of the sleeves being foldable and 95 having their respective inner and outer faces of a design corresponding with the design of the similar sections and sleeves respectively, and said sections being adapted to be reversed from back to front with the sleeves 100 arranged likewise to present either side of the shirt foremost with the design of the sides appearing accordingly.

105 In testimony whereof I affix my signature.
GEORGE O. OLSEN.
